UNITED STATES PATENT OFFICE.

MARTIN W. BRUESHABER, OF CHICAGO, ILLINOIS, ASSIGNOR TO GOSS PRINTING PRESS COMPANY, A CORPORATION OF ILLINOIS.

PRINTING PRESS.

Application filed August 20, 1924. Serial No. 733,115.

The invention relates to printing presses, and more particularly to reversible driving mechanism for rotary web presses.

Objects and advantages of the invention 5 will be set forth in part hereinafter and in part will be obvious herefrom, or may be learned by practice with the invention, the same being realized and attained by means of the instrumentalities and combinations 10 pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:

Fig. 1 is a side elevation, partially diagrammatic, of a press constructed in accordance with the invention;

25 Fig. 2 is a diagrammatic end elevation, looking at Fig. 1 from the right;

Fig. 3 is a fragmentary detail, in elevation, greatly enlarged, of the lower central part of Fig. 1;

30 Fig. 4 is an elevation, with parts in-section, of the upper part of Fig. 3, looking thereat from the right;

Fig. 5 is a diagrammatic perspective, showing one relation of the driving mechanism for driving in one direction; and

35 Fig. 6 is a similar view showing the mechanism arranged to drive the printing cylinders in the opposite direction.

The invention is directed to improvements in fast rotary web presses of the newspaper 40 or magazine class, whereby a large variety of products may be secured from a press of a given construction, including multi-colored products, such as the colored magazines and comic sections of newspapers. The present 45 invention is directed primarily to novel driving mechanism for the various printing couples, each printing couple being individually driven from a common driving shaft, vertically disposed at the side of the 50 press, the general arrangement of such a driving mechanism being shown and de-

scribed in Patents No. 700,100 and No. 700,101 to Goss, dated Aug. 19, 1902.

The invention is shown exemplarily embodied herein in that type of rotary web press wherein two vertically-disposed series or groups of printing couples are arranged at either side of an open space, with the impression or blanket cylinders next to the open space, on either side, so that each of 60 the impression or blanket cylinders may be readily accessible for changing the blanket, making ready, etc., which type of machine is broadly shown and described in Patent No. 528,233 to Michaud dated October 30, 1894. The broad idea of independent reversible gearing or drive for a press of this type is shown and described in Patent Number 555,460 to Michaud, dated Feb. 25, 1896.

While the present invention is exemplarily disclosed applied to a press of the general Michaud type, and to a vertically disposed shaft drive of the type shown in the Goss patents mentioned, the novel features of my reversible drive mechanism are equally applicable to other general types of presses, and in its more important feature it is to a great degree independent of the type of press in which it may be incorporated and used.

In the present preferred embodiment, broadly considered, the printing couples are arranged in vertically-disposed series or rows, at either side of an open space, on which space the impression cylinder of each printing couple faces. A driving shaft for all the printing couples of a vertical series is vertically disposed at one side or end of the series of printing couples, but without being in any essential relation to either the 85 form cylinders or impression cylinders of the various printing couples. Fixed on this vertical driving shaft is a beveled gear for each printing couple, and meshing therewith is a continuously intermeshing beveled gear. 90 This latter beveled gear is in driving relation with a spur gear, preferably at the opposite side of the press therefrom.

Meshing with this spur gear are two gear wheels, one on the shaft of the form cylinder and the other on the shaft of the impression cylinder, these two gear wheels

being alternatively and selectively movable or otherwise attended to. The inking mechanism for the second printing couple in Fig. 1 is shown in retracted position, while those for the other printing couples are shown in operative relation with their respective plate cylinders. So far as concerns the general features of the present invention, the particular form of inking mechanism is immaterial.

5. The selective and alternative slipping of these two gears into and out of mesh with the driving gear constitutes means for driving the printing couples selectively in either direction. The two cylinders of the printing couple are caused to rotate in unison by means of two continuously meshing gears, one on the shaft of the form cylinder and the other on the shaft of the impression cylinder.

15. It will be understood that the foregoing general description of the present preferred embodiment of the invention and likewise the following full detailed description is illustrative and explanatory only, but is not 20 restrictive of the invention. It will be understood further that certain features, objects and advantages of the invention will be primarily set forth in connection with the ensuing detailed description.

25. Referring now in detail to the embodiment, illustrated by way of example in the accompanying drawings, the invention is shown applied to a four-deck newspaper press adapted to perfect a single web in a 30 plurality of colors, or to print a plurality of webs on one side, or to perfect them in a single color, or in a plurality of colors, dependent upon the number of webs, the arrangement thereof in the press, and the direction of rotation selected for different 35 printing couples.

The source of web supply is not shown, but a plurality of web rolls are usually in operative relation at the left hand of Fig. 40. These sources of web supply will be adequate in number and may be of any known or suitable form so far as concerns the main features of the present invention.

A plurality of printing couples are arranged one above another, and are shown as 45 four in number, the first couple comprising impression cylinder 1 and form cylinder 2, the second including impression cylinder 3 and form cylinder 4, the third having impression cylinder 5 and form cylinder 6, and the fourth having impression cylinder 7 and form cylinder 8. The inking mechanism for the first printing couple is indicated diagrammatically by 9, that of the second 50 printing couple by 10, that for the third printing couple by 11 and that for the fourth by 12.

These inking mechanisms are preferably of the usual type, which is mounted on a 55 carriage movable to and fro on the machine frame from operative position with respect to the form or plate cylinder, to a retracted position leaving space for the plates to be changed on the form cylinder and for the 60 inking mechanism to be cleaned, replenished

70 or otherwise attended to. The inking mechanism for the second printing couple in Fig. 1 is shown in retracted position, while those for the other printing couples are shown in operative relation with their respective plate cylinders. So far as concerns the general features of the present invention, the particular form of inking mechanism is immaterial.

75 The second series or group of vertically disposed printing couples is generally similar to the first, and is spaced away therefrom in the press to leave room for the passage of a workman between the two series, and has the impression or blanket cylinders 80 facing on this open space as disclosed in the Michaud patents already referred to. The first printing couple in this second series comprises an impression cylinder 20 and a form cylinder 21, the second couple comprising an impression cylinder 22 and a form cylinder 23, the third couple comprising an impression cylinder 24 and a form cylinder 25 and the fourth couple comprising an impression cylinder 26 and a form 85 cylinder 27. The respective inking mechanisms are represented diagrammatically at 28, 29, 30 and 31, each of these being shown in the operative position with respect to its form or plate cylinder.

90 The general frame structure of the press comprises a plurality of F-shaped members, each member being two decks high, and having each an upright member 32 and two cross members 33 and 34. The two members constituting a frame unit are right-handed and left-handed with respect to each other, and their cross reaches 33 and 34 are bolted together at 35 and 36. A similar construction and arrangement may be used 95 and is shown for each pair of printing couples and each pair of decks. A plurality of bracing or cross pieces 37 may be employed between the different press units.

100 Any suitable folding mechanisms may be employed, as may be found advisable or desirable with the particular type or construction of press wherein the invention is embodied, and in the drawings, a pair of longitudinally disposed single formers 39 and 40 are shown with cooperating cross-folders 41 and 42. It will be understood, however, that these may be selected and varied as desired. A slitter 43 for centrally or otherwise slitting the web is shown diagrammatically, a turner bar or system of turner bars 44 being also similarly shown.

110 Referring now more particularly to the details of the press drive, a driving shaft 54 is shown arranged longitudinally beneath and alongside the press, and this may be provided with any usual or suitable throw-out clutch, reversible gearing drive, or any other desired or convenient connection. Fixed on shaft 54 is a bevel gear wheel 115

55, which meshes with a bevel gear wheel 56, fixed on a vertically-disposed driving shaft 57. This shaft has individual driving connection with each printing couple, but 5 is not in any essential relation to the shafts of either the impression cylinders or the plate cylinders, as the shaft does not drive directly onto the cylinders of the printing couples, but the direction-reversing gear- 10 ing is interposed between the gear wheels on this shaft and the cylinders of the printing couple.

Shaft 57 is supported in bearings 58, 59, 60, 61 and 62, carried on the side frame of the press, and has fixed thereto single bevel gears 63, 64, 65 and 66, one for each printing couple. Meshing with these bevel gear wheels, are corresponding bevel gears 68, 69, 70 and 71, which are in turn fixed to 20 corresponding transversely-disposed shafts, journaled in the machine frame. The bevel gears on the vertically disposed driving shaft 57 and the bevel gears driven thereby are continuously in mesh.

25 Referring especially to Figs. 3 and 4, which may be considered exemplary of the mechanism for each of the printing couples, the bevel gear wheel 63 is in fixed position upon the shaft 57, and is continually in mesh with the bevel gear 68, likewise already referred to. Bevel gear wheel 68 is fixed on a shaft 90, having bearings 91 and 92 in the side frames of the press, the shaft extending across the press parallel to the 30 shafts of the form cylinder and impression cylinder of the particular printing couple. On the opposite side of the press shaft 90 projects beyond the side frame, and fixed thereon is a spur gear wheel 93.

40 The shaft 94 of the impression cylinder 1 has bearings 95 and 96 in the side frames of the press. The shaft 97 of the form cylinder 2 has bearings 98 and 99 in the side frames of the press. Means are provided for insuring the plate and impression cylinders rotating in unison at all times, and for this purpose, a spur gear 100 is fixed to shaft 94 of the impression cylinder, and a spur gear 101 is fixed on the shaft 50 97 of the plate cylinder 2, these two gears being continuously in mesh.

In the embodied form of selective reversible drive, there is mounted on the shaft 94 of the impression cylinder, preferably 55 exterior to the side frame of the press and at the opposite side a spur gear 106. Gear 106 is fixed to shaft 94 to always rotate therewith, but is slidable along the shaft into and out of mesh with the spur gear 93 on the shaft 90. For this purpose gear 106 has a clamping screw 107 in the hub, and it is mounted on shaft 94 by means of a spline or feather 108 fixed to the shaft. Likewise, a spur gear 109 is mounted in like 60 65 position on shaft 97 of the plate cylinder

2, to always rotate therewith, but is also slidable into and out of mesh with the gear wheel 93. For this purpose the hub of gear 109 is provided with a clamping screw 110, and the gear wheel is mounted on the shaft 70 97 by a spline or feather 111 fixed to the shaft.

Thus by alternatively and selectively sliding gear wheels 106 and 109 into and out of mesh with gear wheel 93, the printing couple 75 is driven in either direction as desired, the gears 100 and 101 always insuring the cylinders of the printing couple rotating together in unison, and the bevel gear drive from the general shaft being always in 80 mesh.

In the perspective diagram of Figs. 5 and 6, the relations of the gear wheels, driving in either direction is shown, the arrows on the wheels showing the direction of rotation in both cases. The printing cylinders and many other parts are omitted from these diagrams. In Fig. 5 gear wheel 106 is slipped, and gears 93 and 109 are in mesh, and drive the printing couple in one direction, as indicated, by the arrows on gears 90 100 and 101. In Fig. 6 gear wheel 109 is slipped, and gears 93 and 106 are in mesh, driving the printing couple in the opposite direction, as indicated by the arrows on 95 gears 100 and 101.

From all the foregoing it will be understood that a mechanism has been provided constituting an exemplary embodiment of the invention, and realizing the objects and advantages herein set forth, together with other objects and advantages. It will be understood further that departures may be made from the exact mechanism as shown and described, within the scope of the accompanying claims, without departing from the principles of the invention and without sacrificing its chief advantages.

What I claim is:—

1. A printing press including in combination a plurality of printing couples, a common driving shaft therefor, a driving gear wheel on the driving shaft for each printing couple, a driven gear wheel continuously in mesh with said driving gear and a slip gear 110 reversing mechanism between said driven gears and their printing couples.

2. A printing press including in combination a plurality of printing couples, a common driving shaft therefor having fixed 120 thereon against longitudinal movement a plurality of permanently meshed driving gears, direct connections from each of said driving gears to one of said printing couples, each of said connections including a slip gear reversing mechanism.

3. A printing press including in combination a plurality of printing couples, common driving means therefor at one side of the press, direct connections from said common 130

4. A printing press including in combination a plurality of printing couples, common driving means therefor, direct connections from said common driving means to each printing couple, said connections comprising a slip gear reversing mechanism, on the printing cylinder shafts.
5. A printing press including in combination a plurality of printing couples, common driving means therefor at one side of the press, direct connections from said common driving means to each printing couple, said connections comprising a slip gear reversing mechanism at the opposite side of the press on the printing cylinder shafts.
6. A printing press including in combination a plurality of printing couples, a common driving shaft therefor, a driving gear wheel on the driving shaft for each printing couple, a driven gear wheel continuously in mesh with said driving gear and a slip gear reversing mechanism between said driven gears and their printing couples including a gear wheel on the shaft of a printing cylinder.
7. A printing press including in combination a plurality of printing couples, a common driving shaft therefor at one side of the press, a driving gear wheel on the driving shaft for each printing couple, a driven gear wheel continuously in mesh with said driving gear and a slip gear reversing mechanism between said driven gears and their printing couples, including a gear wheel on the shaft of a printing cylinder at the opposite side of the press.
8. A printing press including in combination a plurality of printing couples, common driving means therefor, direct connections from said common driving means to each printing couple, said connections comprising continuously intermeshing bevel gears and a slip gear reversing mechanism.
9. A printing press including in combination a plurality of printing couples, common driving means therefor at one side of the press, direct connections from said common driving means to each printing couple, said connections comprising continuously intermeshing bevel gears and a slip gear reversing mechanism at the opposite side of the press.
10. A printing press including in combination a plurality of printing couples, common driving means therefor, direct connections from said common driving means to each printing couple, said connections comprising continuously intermeshing bevel gears and a slip gear reversing mechanism on the printing cylinder shafts.
11. A printing press including in combination a plurality of printing couples, com-
- mon driving means therefor at one side of the press, direct connections from said common driving means to each printing couple, said connections comprising continuously intermeshing bevel gears and a slip gear reversing mechanism at the opposite side of the press on the printing cylinder shafts.
12. A printing press including in combination a plurality of printing couples, common driving means therefor, direct connections from said common driving means to each printing couple, said connections comprising continuously intermeshing bevel gears and a slip gear reversing mechanism including a gearwheel on the shaft of a printing cylinder.
13. A printing press including in combination a plurality of printing couples arranged in a vertical series, a common vertical driving shaft therefor, a continuously intermeshing gear drive on the shaft for each printing couple and a slip gear reversing mechanism between said intermeshing drive and the printing couple.
14. A printing press including in combination a plurality of printing couples arranged in a vertical series, a common vertical driving shaft therefor, a continuously intermeshing gear drive on the shaft for each printing couple and a slip gear reversing mechanism between said intermeshing drive and the printing couple including a gear on a printing cylinder shaft.
15. A printing press including in combination a plurality of printing couples arranged in a vertical series, a common vertical driving shaft therefor, a continuously intermeshing gear drive on the shaft for each printing couple and a slip gear mechanism between said intermeshing drive and the printing couple including a gear on each cylinder shaft of the printing couple.
16. A printing press including in combination a plurality of printing couples arranged in a vertical series, a common vertical driving shaft therefor at one side of the press, a continuously intermeshing gear drive on the shaft for each printing couple and a slip gear reversing mechanism between said intermeshing drive and the printing couple including a gear on a printing cylinder shaft at the opposite side of the press.
17. A printing press including in combination a plurality of printing couples arranged in a vertical series, a common vertical driving shaft therefor at one side of the press, a continuously intermeshing gear drive on the shaft for each printing couple and a slip gear mechanism between said intermeshing drive and the printing couple including a gear on each cylinder shaft of the printing couple at the opposite side of the press.
18. A printing press including in combination a plurality of printing couples ar-

ranged in a vertical series, a common vertical driving shaft therefor, a gear drive on the shaft for each printing couple and a slip gear reversing mechanism between said intermeshing drive and the printing couple.

19. A printing press including in combination a plurality of printing couples arranged in a vertical series, a common vertical driving shaft therefor, a gear drive on the shaft for each printing couple and a slip gear reversing mechanism between said intermeshing drive and the printing couple including a gear on a printing cylinder shaft.

20. A printing press including in combination a plurality of printing couples arranged in a vertical series, a common vertical driving shaft therefor, a gear drive on the shaft for each printing couple and a slip gear mechanism between said intermeshing drive and the printing couple including a gear on each cylinder shaft of the printing couple.

21. A printing press including in combination a plurality of printing couples arranged in a vertical series, a common vertical driving shaft therefor at one side of the press, a gear drive on the shaft for each printing couple and a slip gear reversing mechanism between said intermeshing drive

and the printing couple including a gear on a printing cylinder shaft at the opposite side of the press.

22. A printing press including in combination a printing couple and driving mechanism therefor including a continuously driven gear wheel and a slip gear on each shaft of the couple selectively movable into mesh with the continuously driven gear.

23. A printing press including in combination a printing couple and driving mechanism therefor including a continuously driven gear wheel and a slip gear on each shaft of the couple selectively movable into mesh with the continuously driven gear and means for causing the printing cylinders to rotate in unison.

24. A printing press including in combination a printing couple and driving mechanism therefor including a continuously driven gear wheel and a slip gear on each shaft of the couple selectively movable into mesh with the continuously driven gear and intermeshing gears mounted on, and fixed to rotate with, the printing cylinder shafts.

In testimony whereof, I have signed my name to this specification.

MARTIN W. BRUESHABER.
